UNITED STATES PATENT OFFICE.

MORRIS HIRSHFIELD, OF BROOKLYN, NEW YORK.

DESIGN FOR A SLIPPER.

60,660.

Specification for Design. Patented Mar. 21, 1922.

Application filed November 16, 1921. Serial No. 515,696. Term of patent 3½ years.

To all whom it may concern:

Be it known that I, MORRIS HIRSHFIELD, a citizen of the United States, and resident of the borough of Brooklyn, county of Kings, city and State of New York, have invented a new, original, and ornamental Design for Slippers, of which the following is a specification.

In the accompanying drawings, Fig. 1 is a plan view of a slipper showing my new design, and Fig. 2 is a side elevation thereof.

The design comprises a band *a* of velvet or other material of the silk type, upon the surface of which a scroll *b* is located, said

band *a* being edged with a cord *c* and having its forward ends terminating at a pom pom *d*. The whole is applied to a slipper of felt as a border, the distinctive contrast between the velvet band and the felt slipper being a part of the design.

It is to be understood that my claim includes all substantial equivalents of my design, as shown and described.

I claim:

The ornamental design for a slipper as shown and described.

MORRIS HIRSHFIELD.
